Primary Examiner — Cynthia M Chin*(74) Attorney, Agent, or Firm* — Greer, Burns & Crain, Ltd.(57) **CLAIM**

The ornamental design for a trailer for children's vehicle, as shown and described.

DESCRIPTION

FIG. 1 is a perspective view of a trailer for children's vehicle showing my new design.

FIG. 2 is a perspective view of the trailer for children's vehicle shown in FIG. 1 in a first of multiple alternate positions.

FIG. 3 is a perspective view of the trailer for children's vehicle shown in FIG. 1 in a second of multiple alternate positions.

FIG. 4 is a side elevational view of the trailer for children's vehicle shown in FIG. 1.

FIG. 5 is an elevational view of the other side thereof.

FIG. 6 is a front elevational view thereof.

FIG. 7 is a rear elevational view thereof.

FIG. 8 is a top plan view thereof; and,

FIG. 9 is a bottom view thereof.

The portions of the article shown in broken lines form no part of the claimed design.
